UNITED STATES PATENT OFFICE

LEO OWEGER AND GEORGE SCHOETTINGER, OF DAYTON, OHIO, ASSIGNORS TO THE MULTIPLE VALVE AND MANUFACTURING COMPANY, OF DAYTON, OHIO, A CORPORATION OF OHIO

VALVE-OPERATING DEVICE

Application filed March 14, 1929. Serial No. 347,078.

This invention relates to a valve operating device and is designed more particularly for use on a multiple valve comprising a plurality of separately operable valve members. In multiple valves as heretofore constructed it has been customary to selectively actuate the valve members by means of a rotary cam which engages the ends of the valve stems with a transverse wiping action and thus subjects the same to a lateral thrust which not only is very destructive of the packing, and tends to cause the valves to leak, but also tends to distort and otherwise injure the valve stems.

One object of the present invention is to provide means for selectively actuating the valves with a straight line thrust in the direction of the length of the valve stems.

A further object of the invention is to provide such an operating device having a single actuating member or handle for selectively positioning the selecting means and for actuating the valve members.

A further object of the invention is to provide such an operating mechanism with means for preventing the operative movement thereof except when the selecting device is properly positioned with relation to the selected valves, and to prevent the movement of the selecting device with relation to the valve stems during the operation of the latter.

A further object of the invention is to provide such an operating device which will be simple in its construction and operation and of a strong durable character.

Other objects of the invention will appear as the apparatus is described in detail.

In the accompanying drawings Fig. 1 is a vertical sectional view of a multiple valve showing the selecting and actuating devices in elevation, with the handle partly broken away; Fig. 2 is a section taken on the line 2—2 of Fig. 1, partly broken away; Fig. 3 is a section taken on the line 3—3 of Fig. 1; Fig. 4 is a section taken on the line 4—4 of Fig. 3, looking in the direction of the arrows; and Fig. 5 is a section taken on the line 5—5 of Fig. 3.

In these drawings we have illustrated one

embodiment of our invention and have shown the same as applied to a multiple valve of the type shown and described in the application filed by John B. Aufuldish on February 28, 1927, Serial No. 171,476, but it will be understood that this particular embodiment has been chosen for the purposes of illustration only and that the operating mechanism may take various forms and may be applied to valves of various kinds.

In that particular embodiment of the invention here illustrated the multiple valve comprises a casing 1 having a plurality of passageways or valve chambers 2 each of which is provided with a valve seat 3. Valve members 4 are mounted in the passageways for movement into and out of engagement with the valve seats, each valve member having a downwardly extending stem 5. The casing is provided in its bottom wall with openings 6 arranged in line with the respective valve seats 3 and these openings are closed by screw plugs 7, each having an inwardly opening cavity 8. Ferrules 9 are mounted on the lower ends of the valve stems and are slidably mounted in the cavities 8. Springs 10 are confined between the ferrules and the bottom walls of the respective cavities and serve to press the valves toward their seats. In this manner the spring is removed from the passageway or valve chamber so that it does not obstruct the flow of fluid therethrough and, further, the arrangement of the springs in the cavities 8 where they are not in direct contact with the fluid minimizes the injurious effect of certain fluids, such as steam, upon the springs. Each valve member 4 also has an upwardly extending valve stem 11 which extends through an elongated boss 12 and packing gland 13 and projects a short distance above the packing gland. The details of construction of the valve casing and its passageways are not essential to an understanding of the present invention and therefore not shown or described. It will be noted, however, that in the present valve there are four separately operable valve members which are spaced apart about the vertical center of the casing

and which may be grouped in any desired arrangement, the valve stems being shown at 11, 11a, 11b, and 11c.

For the purpose of selectively operating the several valve members 4 we provide a selecting device having parts adapted to be moved transversely to the length of the valve stems 11 into and out of alignment with selected valve stems. Means are also provided for imparting movement to this selecting device in the direction of the length of the valve stems so that those parts thereof which have been moved into line with valve stems will engage those valve stems and actuate the same with a straight axial thrust. In the present construction a stud 14 is rigidly secured to the valve casing and it projects upwardly therefrom to a point some distance beyond the upper ends of the several valve stems, this stud being in the present instance arranged centrally of the casing. The valve casing is provided with a recess 15 in the upper part thereof which surrounds the stud 14. The selecting device is here shown as a disk-like member 16 and is slidably and rotatably mounted upon the stud 14. Preferably it is provided with a depending bearing portion or hub 17, the lower end of which extends into the recess 15 in the casing. A spring 18 is confined between the casing and the disk-like member 16 and tends to hold the latter normally in its elevated position. The actuating device further comprises a plurality of parts which depend from the disk-like member 16 and are so arranged with relation thereto that they may be moved into and out of line with selected valve stems. These projections may be of any suitable character and, in the present instance, we have utilized two forms of projections. In one instance lugs 19 are formed integral with the disk-like member 16. In the other instance the projection is in the form of a screw 20 threaded through the member 16 and locked in position thereon by a nut 21. In this manner the projection is made adjustable with relation to the disk-like member 16, thereby enabling the amount of movement imparted to the valve stem by a given movement of the selecting device to be varied so as to cause the valves to be opened different distances.

The multiple valve here illustrated is designed primarily for use on a bakelite press and in the operation of such a press the bakelite or material to be molded is first placed in the mold and the mold closed, then the steam is circulated about the mold to heat the same while pressure is being applied thereto. After the molding operation is completed the steam is shut off and cold water circulated about the mold to cool the same. The steam inlet is then connected with the mold and the mold is connected with the drain so as to discharge the water therefrom. The

inlets and outlets for the steam and water are all arranged within the single valve casing and in the control of the same the valves are operated in pairs. First the steam inlet and the steam outlet valves are opened, then the water inlet and water outlet valves are opened, and then the steam inlet and water outlet valves are opened. In the present operating mechanism the projections on the selecting device are so arranged that when the selecting device is rotated to any one of three predetermined positions two of the lugs or projections thereon will be in line with the stems of the valve members which are to be operated.

Any suitable means may be provided for depressing the selecting device to cause the projections to engage the valve stems with which they are in line and to impart axial movement thereto. Preferably a single handle serves both to rotate the selecting device and to impart axial movement thereto thus enabling the selecting device to be very quickly positioned and actuated.

In the particular construction here illustrated the selecting member or disk 16 has on its upper surface two bearings 22 arranged on opposite sides of the stud 15, these bearings being preferably formed integral with the member 16. Journaled in the respective bearings 22 are two cylindrical members or trunnions 23, the inner ends of which extend inwardly beyond the respective bearings and are flattened on one side as shown at 24. These inwardly extending portions of the trunnions project beneath a shoulder carried by the fixed stud 14 and which, in the present instance, comprises a collar 25 mounted on the stud and held in position thereon by a nut 26. When rotatory movement is imparted to the trunnions the cam shaped inner portions thereof will engage the collar 25 and acting against the same will force the selecting device 16 downwardly, the throw of the cams being sufficient to impart the desired movement to the valve stems. The trunnions are preferably actuated by a handle 27, the lower portion of which is bifurcated and the respective arms 28 thereof rigidly secured to the outer ends of the respective trunnions. In the present device each arm of the handle is provided on opposite sides of its axis with inwardly extending parts 29 forming between them a longitudinal slot and each trunnion has at its outer end an outwardly extending lug 30, which enters the slot in the corresponding arm, the lugs and the slots being so shaped as to hold the parts against relative rotation. Screws 31 serve to hold the arms of the handle against displacement with relation to the trunnions. The shape of the cam portions 24 of the trunnions is such that axial movement may be imparted to the selecting device by the movement of the handle in either direc-

tion about its transverse axis, but inasmuch as it is desired to operate the selecting device by the movement of the handle in one direction only we have provided the arms 28 of the handle with stops 32 arranged to engage the disk 16 and prevent the movement of the handle in one direction about this transverse axis.

It will be apparent that by grasping the handle 27 and rotating the same about the vertical axis of the selecting device that the device may be moved to the desired position and by then exerting a forward pull on the handle 27 the selecting device is depressed to actuate the valve members. To facilitate the correct positioning of the selecting device with relation to the valve stems, to cause the operation of the desired valve members, stops are provided. As here shown, a stud 33 extends upwardly at one side of the casing and terminates just below the normal position of the disk 16 of the selecting device. To accurately position the selecting device in its extreme positions stops 34 depend therefrom and are arranged to engage the stud 33. To position the selecting device in its third or intermediate position a yieldable detent 35 is mounted in the upper portion of the casing 1 and arranged to enter a groove 36 in the hub portion 17 of the selecting device, this groove being so arranged that when the selecting device is in its correct intermediate position the detent will enter the groove and resist the further movement thereof but will yield when pressure is applied to the selecting device.

It is also desirable that means should be provided to prevent the axial movement of the selecting device when the latter is not accurately located in any operative position and to prevent the rotatory movement of the selecting device when the latter has been moved from its normal position. To this end the rear portion of the disk-like member 16, which overhangs the upper end of the stud 33, is provided with a series of openings or recesses 37 so arranged that when the selecting device is in any one of its three predetermined positions one of the openings 37 will be in line with the stud 33, thereby permitting the downward movement of the selecting device. After the selecting device has been moved downwardly from its normal position and the stud 33 has entered one of the recesses 37 the selecting device cannot be rotated until it is returned to its uppermost or normal position. Preferably the lower edges of the notches 37 are slightly beveled to facilitate the entrance of the stud into the same.

While we have shown and described one embodiment of our invention we wish it to be understood that we do not desire to be limited to the details thereof as various modi-

fications may occur to a person skilled in the art.

Having now fully described our invention, what we claim as new and desire to secure by Letters Patent, is:

1. In an operating device for a multiple valve comprising a plurality of separately operable valve members each having a stem by means of which it may be actuated, a selecting device having a part movable into and out of line with one of said valve stems and movable in the direction of the length of said valve stem to cause said part to engage said valve stem and actuate the valve member with which it is connected, and a single device for imparting both movements to said part of said selecting device.

2. In an operating device for a multiple valve comprising a plurality of separately operable valve members each having a stem by which it may be actuated, a selecting device mounted for rotatory movement into and out of line with one of said valve stems and for axial movement to actuate said valve stem and the valve member with which it is connected, and a handle movable in one direction to rotate said selecting device and in another direction to impart axial movement thereto.

3. In an operating device for a multiple valve comprising a plurality of separately operable valve members each having a stem by which it may be actuated, a selecting device having a part normally fixed with relation thereto and movable therewith into and out of line with one of said valves, said selecting device being movable as a whole in the direction of the length of said valve to cause said part to engage said valve stem and impart longitudinal movement thereto, said part being adjustable with relation to said selecting device to vary the amount of movement imparted thereby to said valve stem, and an operating device to impart both movements to said selecting device.

4. In an operating device for a multiple valve comprising a plurality of separately operable valve members each having a stem by means of which it may be actuated, a selecting device movable transversely to said valve stems into operative relation with a selected valve stem, and movable lengthwise of the selected valve stem to actuate the same, and a single device for imparting both selecting movement and actuating movement to said selecting device.

5. In an operating device for a multiple valve comprising a plurality of separately operable valve members each having a stem by means of which it may be actuated, a selecting device mounted for rotatory movement and for axial movement and having a part fixed with relation thereto and arranged to be moved into and out of line with one of said valve stems by the rotatory movement of said selecting device, and means for impart-

ing axial movement to said selecting device as a whole to cause said part to engage and actuate said valve stem.

6. In an operating device for a multiple valve comprising a plurality of separately operable valve members each having a stem by means of which it may be actuated, a selecting device mounted for rotatory movement and for axial movement and having a part fixed with relation thereto and arranged to be moved into and out of line with one of said valve stems by the rotatory movement of said selecting device, a cam to impart axial movement to said selecting device as a whole, and a handle to operate said cam.

15 a handle to operate said cam.

7. In an operating device for a multiple valve comprising a plurality of separately operable valve members each having a stem by means of which it may be actuated, a selecting device mounted for rotatory movement and for axial movement and having a part fixed with relation thereto and arranged to be moved into and out of line with one of said valve stems by the rotatory movement of said selecting device, a handle to impart rotatory movement to said selecting device and having movement about an axis transverse to the axis of said selecting device, and means controlled by the movement of said handle about said transverse axis to impart axial movement to said selecting device as a whole.

20

25

30

8. In an operating device for a multiple valve comprising a valve casing and a plurality of separately operable valve members mounted in said casing and each having a stem by means of which it may be actuated, a selecting device mounted on said casing for both rotatory and axial movement and having parts movable into and out of line with the respective valve stems, a stud carried by said casing, and an actuating device operatively connected with said selecting device and with said stud to impart axial movement to said selecting device.

45 9. In an operating device for a multiple valve comprising a valve casing and a plurality of separately operable valve members mounted in said casing and each having a stem by means of which it may be actuated, a
50 selecting device mounted on said casing for both rotatory and axial movement and having parts movable into and out of line with the respective valve stems, a stud carried by said casing, and an actuating device connected
55 with said selecting device to impart rotatory movement thereto and cooperating with said stud to impart axial movement to said selecting device.

10. In an operating device for a multiple valve comprising a valve casing and a plurality of separately operable valve members mounted in said casing and each having a stem by means of which it may be actuated, a selecting device mounted on said casing for both rotatory and axial movement and hav-

ing parts movable into and out of line with the respective valve stems, a stud carried by said casing, and an actuating device carried by said selecting device and comprising a cam arranged to act against a part carried by said stud to impart axial movement to said selecting device.

11. In an operating device for a multiple valve comprising a valve casing and a plurality of separately operable valve members mounted in said casing and each having a stem by means of which it may be actuated, a selecting device mounted on said casing for both rotatory and axial movement and having parts movable into and out of line with the respective valve stems, a stud carried by said casing, projecting beyond said selecting device and having a shoulder, a cam mounted on said selecting device and arranged to engage the shoulder on said stud, and means for actuating said cam.

12. In an operating device for a multiple valve comprising a valve casing and a plurality of separately operable valve members mounted in said casing and each having a stem by means of which it may be actuated, a selecting device mounted on said casing for both rotatory and axial movement and having parts movable into and out of line with the respective valve stems, a stud carried by said casing, projecting beyond said selecting device and having a shoulder, a cam mounted on said selecting device and arranged to engage the shoulder on said stud, means for actuating said cam, and a spring acting on said selecting device to support said parts normally out of contact with said valve stems.

13. In an operating device for a multiple valve comprising a valve casing and a plurality of separately operable valve members mounted in said casing and each having a stem by means of which it may be actuated, a stud carried by said casing, projecting beyond the ends of said valve stems and having a shoulder, a selecting device rotatably and slidably mounted on said stud and having parts arranged to be moved into and out of line with the respective valve stems by the rotatory movement of said selecting device, said selecting device having transverse bearings on opposite sides of said stud, members journaled in the respective bearings and each having a cam shaped portion extending beneath the shoulder on said stud, and a handle connected with said members. 105 110 115 120

14. In an operating device for a multiple valve comprising a valve casing and a plurality of separately operable valve members mounted in said casing and each having a stem by means of which it may be actuated, a stud carried by said casing, projecting beyond the ends of said valve stems and having a shoulder, a selecting device rotatably and slidably mounted on said stud and having parts arranged to be moved into and out of 125 130

line with the respective valve stems by the rotatory movement of said selecting device, said selecting device having transverse bearings on opposite sides of said studs, cylindrical members journaled in the respective bearings and each having an inner portion which is flattened on one side and extends beneath the shoulder on said stud, and a handle having parts secured to the outer ends of the respective cylindrical members.

15. In an operating device for a multiple valve comprising a valve casing and a plurality of separately operable valve members mounted in said casing and each having a stem by means of which it may be actuated, a stud carried by said casing, projecting beyond the ends of said valve stems and having a shoulder, said casing having a recess surrounding said stud, a selecting device rotatably and slidably mounted on said stud and having a hub portion extending into said recess, a spring confined between said casing and said selecting device, cams carried by said selecting device and arranged to engage the shoulder on said stud, and a handle connected with said cams to actuate the same.

16. In an operating device for a multiple valve comprising a valve casing and a plurality of separately operable valve members mounted in said casing and each having a stem by means of which it may be actuated, a disk-like member rotatably and slidably mounted on said casing and having projections depending therefrom and movable into and out of line with the respective valve stems by the rotatory movement of said member, means for positioning said member with a part of said projections in line with selected valve stems, and means for imparting sliding movement to said member to actuate said selected valve stems.

17. In an operating device for a multiple valve comprising a valve casing and a plurality of separately operable valve members mounted in said casing and each having a stem by means of which it may be actuated, a disk-like member rotatably and slidably mounted on said casing and having projections depending therefrom and movable into and out of line with the respective valve stems by the rotatory movement of said member, means for positioning said member with a part of said projections in line with selected valve stems, means for imparting sliding movement to said member to actuate said selected valve stems, and means to prevent the sliding movement of said member when all of said projections are out of line with said valve stems.

18. In an operating device for a multiple valve comprising a valve casing and a plurality of separately operable valve members mounted in said casing and each having a stem by means of which it may be actuated, a disk-like member rotatably and slidably

mounted on said casing and having projections depending therefrom and movable into and out of line with the respective valve stems by the rotatory movement of said member, means for positioning said member with a part of said projections in line with selected valve stems, means for imparting sliding movement to said member to actuate said selected valve stems, and means to prevent the rotatory movement of said member after sliding movement has been imparted thereto and before it has returned to its normal position.

19. In an operating device for a multiple valve comprising a valve casing and a plurality of separately operable valve members mounted in said casing and each having a stem by means of which it may be actuated, a disk-like member rotatably and slidably mounted on said casing and having projections depending therefrom and movable into and out of line with the respective valve stems by the rotatory movement of said member, means for positioning said member with a part of said projections in line with selected valve stems, means for imparting sliding movement to said member to actuate said selected valve stems, and a stop carried by said casing, said member having a part overhanging said stop and provided with openings so arranged that one of said openings will be brought into line with said stop when said member has been moved to a predetermined position.

In testimony whereof, they affix their signatures hereto.

LEO OWEGER.
